CIGARETTE LIGHTER

Kenjiro Goto, Tokyo, Japan, assignor to Mansei Kogyo
Kabushiki Kaisha, Kawaguchi-shi, Saitama, Japan

Filed Mar. 15, 1973, Ser. No. 341,684

Term of patent 14 years

Int. Cl. D27—05

U.S. Cl. D48—27 R

FIG. 1

FIG. 2

FIG. 3

FIG. 4

FIG. 5

FIG. 6

FIG. 1 is a top plan view of a cigarette lighter showing my design;

FIG. 2 is an elevational view as taken from the left of FIG. 1;

FIG. 3 is a front elevational view thereof, the rear having the same appearance;

FIG. 4 is an elevational view as taken from the right of FIG. 1;

FIG. 5 is a bottom plan view thereof;

FIG. 6 is a perspective view thereof.

I claim:

The ornamental design for a cigarette lighter, as shown and described.
